Albert Betteley

United States Patent Office.

ALBERT BETTELEY, OF BOSTON, MASSACHUSETTS.

Letters Patent No. 101,346, dated March 29, 1870.

IMPROVEMENT IN WOOD PAVEMENTS.

The Schedule referred to in these Letters Patent and making part of the same.

To all whom it may concern:

Be it known that I, ALBERT BETTELEY, of Boston, in the county of Suffolk and State of Massachusetts, have invented an Improved Wood Pavement; and I do hereby declare that the following, taken in connection with the drawings which accompany and form part of this specification, is a description of my invention sufficient to enable those skilled in the art to practice it.

This invention is an improvement in wood pavement, made up of cylinders formed from young or small trees, the advantages of such material having been before set forth by me in my patent No. 96,870, dated November 16, 1869, to which reference may be had therefor.

My present invention consists in a wood pavement made up of cylinders of comparatively small diameter, say from about four to seven inches diameter of body, some of which blocks have grooves turned in their peripheries, and others have beads, fillets, or rings formed on their peripheries, preferably integral with the blocks, so that the grooved blocks and the beaded or ringed blocks interlock when placed in position on a road-bed, and mutually support each other from vertical displacement, the blocks being set in a substantially upright position, and their ends and grooves and rings being substantially square to the axes of the blocks which are interspersed as to their relative positions, as will be seen in figs. 1 and 2.

Figure 1 of the drawings shows, one-half in plan and one-half in horizontal section, a piece of pavement made in accordance with my invention.

Figure 2 shows in plan a piece of pavement embodying my invention, in which the arrangement of the grooved and ringed blocks differs somewhat from that shown in fig. 1.

In said figure it will be seen that each ringed block is surrounded by six grooved blocks, and that the same is the case in fig. 2. In fig. 1, however, the arrangement of the blocks is such that in each row taken in any right line of direction will be found both ringed and grooved blocks; and, on inspection of said figure, it will further be seen that the system is such that each grooved block is supported by the interlocking therewith of three ringed blocks.

In fig. 2 it will be seen that in one direction there is a row of grooved blocks, and a row of blocks in which grooved and ringed blocks alternate, then a row

of grooved blocks, and next a row of grooved and ringed blocks, and so on throughout the pavement.

In this arrangement each grooved block is supported by the interlocking therewith of two ringed blocks.

The ringed blocks are marked *a*, and the grooved blocks *b*, in all the figures.

Figure 3 is a vertical section, taken in the line *z z*, fig. 1, and the tops of these blocks are shown as slightly rounded, which may, in some locations, be deemed desirable to afford a foothold for horses, though if the blocks are left flat at the outset, they will naturally wear rounding on top, as shown in fig. 3.

Figure 4 is a section taken on the line *y y*, fig. 1, showing the ringed blocks in section, and the grooved blocks in elevation beyond.

Figure 5 is a section taken in the line *x x*, fig. 1, showing the grooved blocks in section.

Figure 6 is a section taken in the line *w w*, fig. 2, showing the alternate grooved and ringed blocks in one row.

Figure 7 is a section taken in the line *r r*, fig. 2, showing the grooved blocks of a row only.

It will be seen that the ringed and grooved blocks interlock and mutually support each other against vertical displacement, and that the spaces left between the blocks afford a good hold for the feet of horses, so that they will not slip upon the pavement.

Each block is also supported by six vertical lines of contact with its neighbors, besides being supported with the sand, gravel, or other material which is to be filled into the interspaces.

The bodies of the blocks forming a pavement are to be made of uniform diameter, that is, the ringed blocks, above and below the ring on each, are to be of the same diameter as the grooved blocks above and below the groove in each.

More than one groove and more than one ring, or the equivalent of the ring, may be employed, though I consider one at about the center of the length of each block as sufficient.

I claim a pavement made up of cylindrical blocks, interlocked substantially as described.

ALBERT BETTELEY.
